FLEXIBLE APERTURED PANELS
Meyer J. Ragir, Highland Park, Ill., assignor to Selfix,
Inc., a corporation of Illinois
Filed June 1, 1966, Ser. No. 554,521
4 Claims. (Cl. 211—87)

This invention relates to flexible apertured panels adapted for mounting on surfaces, and, more particularly, to strengthened panels having increased weight carrying capabilities.

The use of apertured boards for supporting hooks and other hanging elements designed to carry or display articles is well known. One disadvantage of such structures, however, is the rigidity and weight of the material in which the apertures are formed. These boards are usually used in a fixed display stand or more commonly attached to a wall or other supporting surface. In affixing such boards to supporting surfaces, not only is it necessary to solidly anchor the boards to the surface, but it is also usual to provide for spacing between the supporting surface and the apertured board to allow the hooks or other elements attached thereto to pass through the apertures and to lock against the rear surface of the board.

In order to overcome many of these disadvantages, it has been proposed to use thin flexible panels which may readily be attached to walls or other supporting surfaces such as by an adhesive. Such thin panels can be mounted around curved surfaces and otherwise conform to the shape of the surface on which they are mounted. These flexible panels, which may conveniently be made of a thermo-plastic polymer film or thin sheet, usually have formed therein raised embossments into which the hooks are inserted. Since one advantage of such panels is their light weight and their flexible properties, they have limited weight carrying capabilities.

The hooks or hanging elements, which are attached to the panels through apertures in the embossments, are usually provided with offset ends which pass through the apertures and bear against either the front or side walls of the embossments. Since it is desirable to be able to orient the panel in more than one direction, the shape of the embossments is usually symmetrical and conveniently may have a circular periphery.

In accordance with the present invention, there are provided means associated with each of the raised embossments for increasing the rigidity of such embossments and for increasing the weight carrying capabilities of the flexible panel. This additional strength may be effected by the provision of members formed integral with the embossment or by altering the overall configuration of the embossments themselves, whereby the strength of the entire panel may be increased.

In one suitable configuration, the embossments may conveniently be rectangular in shape in which the longer edges of adjacent rectangles would be perpendicular to each other. In this way, it would still be possible to orient the panel in more than one position since the offset ends of the hooks would fit into one embossment in one direction and into the next adjacent embossment when rotated 90°. If it is desirable to have more symmetrical embossments, they may be formed as cruciforms rather than alternately arranged rectangles.

The flexible panel of the present invention not only retains the desired characteristics of flexibility, light weight, convenience and easy application to a supporting surface, but provides such a flexible apertured panel with increased strength and load carrying capabilities.

Numerous other advantages and features of the present invention will become readily apparent from the following detailed description of the invention and one embodiment

2

thereof, from the claims, and from the accompanying drawings in which each and every detail shown is fully and completely disclosed as part of the specification, and in which like reference numerals refer to like parts, and in which

FIGURE 1 is a plan view of a suitable panel according to the present invention showing a hook or hanging element in place and attached thereto;

FIGURE 2 is an enlarged section of an embossment taken along the lines 2—2 of FIGURE 1 showing one embodiment for increasing the strength of such embossment;

FIGURE 3 is a sectional view showing a modification of the embodiment of FIGURE 2;

FIGURE 4 is an enlarged plan view of one embossment showing another configuration for increasing the rigidity thereof;

FIGURE 5 is a sectional view taken along lines 5—5 of FIGURE 4;

FIGURE 6 is a plan view showing a modification of the embodiment of FIGURE 5;

FIGURE 7 is a sectional view taken along the lines 7—7 of FIGURE 6;

FIGURE 8 is a plan view of a flexible panel in which the rectangular embossments are formed in the panel;

FIGURE 9 is a partial section of the panel taken along the lines 9—9 of FIGURE 8;

FIGURE 10 is a plan view of another embodiment of the flexible panel in which the embossments are shown in the shape of cruciforms;

FIGURE 11 is a sectional view of the cruciform panel taken along lines 11—11 of FIGURE 10; and

FIGURE 12 is a perspective view of the cruciform embossment.

Referring to FIGURE 1, there is shown a flexible panel 20 in accordance with the present invention formed from a thin sheet of flexible material typically a suitable thermo-plastic polymer. The panel 20 is provided with a plurality of circular embossments 22 extending out from the front face 24 thereof, each of said embossments having a cylindrical side portion 26 and a front portion 28. The embossments 22 are formed from the flexible material and are integral with the panel 20. An aperture 30 is provided in the front portion 26 of each embossment 22 to accept a hook 32 to be attached to the panel 20.

The hook 32 may be attached to the panel by first inserting one end 34 through aperture 30 in one embossment 22 and then passing a stud formed on the hook through an aperture in an embossment adjacent to the first embossment. Typically, the end 34 of the hook 32 will be offset at 36 from the main body 38 of the hook 32 and when inserted through an aperture 30 of an embossment 22, extends laterally of the aperture within the confines of the side portions 26 of the embossment. Thus, the embossment 22 is provided with sufficient space between the aperture 30 and the inner surface 39 of the side portions 26 to accommodate this offset hook end 34.

As noted above, one advantage of the flexible panels is their ability to conform to the shape of the surface on which they are mounted. Since, as explained above, the embossments 22 extending out from the front face 24 of the panel 20 allow for insertion of the hooks 32 therein, it is possible to mount the panels on a support surface by attaching the rear face 40 directly to the surface without providing a space therebetween. Typically, adhesive means 41 formed on the rear face 40 may be used to mount the panel 20 on the wall or support surface.

The material from which the panel is formed is initially a thin material. As a result, the embossments 22 and the panel 20 have somewhat limited load carrying capabilities. In order to improve the panel's characteristics, the

embossments 22 may be formed with an annular upstanding wall 42 defining the periphery 43 of the aperture 30 passing through the front portion 28 of the embossment 22 and oriented substantially normal to the front face 24 of the panel 20.

Not only does the upstanding annular wall 42 give more support to the end 34 of the hook 32 inserted through the aperture 30, but it may be modified to accommodate other type studs inserted therethrough such as those with enlarged end portions.

Referring to FIGURE 3, an annular upstanding wall 44 defining the periphery 43 of the aperture 30 is provided with a circumferential groove 45 which engages the enlarged end 46 of a hook or stud inserted through the aperture, thereby locking it in place.

As shown in FIGURES 4 and 5, the rigidity of the embossment also may be increased by forming radial rib-like members 48 internally of and integral with the embossment 30. Such radial rib members 48 may extend completely across the inside of the front portion 28 of the embossment 30 between the annular upstanding wall 42 and the inside surface 39 of the side portion 26 of the embossment. Alternatively, as shown in FIGURES 6 and 7, the ribs 52 may be inclined and extend only partially across the front portion 28 of the embossment terminating at a point 54 intermediate the annular upstanding wall 42 and the side portion 26.

Alternatively, the strength of the panel may be increased by altering the shape of the embossments. As shown in FIGURES 8 and 9, the embossments 56 may be conveniently formed in the shape of rectangles having the apertures 30 passing through the front portion thereof. Since each rectangular embossment 56 allows for insertion of the offset hook ends 36 only in one direction, the longer sides 58 of adjacent embossments 56 are disposed perpendicular to each other. This arrangement allows for increased flexibility in mounting the panel 20 on a supporting surface by allowing the hooks 32 to be attached to the panel 20 in two different positions.

The advantage of such rectangular embossments 56 arises from the fact that this shape provides greater strength than does a circular embossment and, therefore, the load carrying capabilities of the panel 20 are increased. If it is desirable to maintain more universally shaped embossments, they may be formed as cruciforms 60, thereby allowing insertion of the offset hook ends 36 in either of two positions, which embossments 60 also provide increased load carrying capabilities. As illustrated in FIGURES 9 and 11, the embossments of the alternative configurations may also be formed with an upstanding annular wall 42 defining the periphery 39 of the aperture 30.

The modified embossments 56, 60 provide an additional advantage when they are formed by vacuum molding. In vacuum molding, the embossments are formed by stretching the thin flexible material of the panel 20. The material is stretched less in forming the rectangular embossments 56 and the cruciform embossments 60 than in forming the circular embossments 22. Since, therefore, the walls of the modified embossments are thicker, the load carrying capabilities of the panel are further increased when formed in this manner. The amount of stretching may be further reduced by forming the modified emboss-

ments with curved surfaces 62 rather than with distinct top and side portions.

The hooks described hereinabove in combination with the panel of the present invention are only examples of the many hanging elements available for use with such panels. It should be understood that such hooks form no part of the present invention, and any suitable hanging elements may be utilized.

It will be readily observed from the foregoing detailed description of the invention and the illustrated embodiments thereof that numerous variations and modifications may be effected without departing from the true spirit and scope of the novel concepts and principles of this invention.

15 What is claimed is:

1. A flexible apertured panel adapted for mounting on a surface and designed to support articles on hook elements attached thereto, said panel being formed from a thin sheet of flexible material having front and rear faces 20 whereby said panel is adapted to conform to the shape of a surface on which it is mounted, and adhesive means provided on said rear face for mounting said panel on a surface, said panel defining a plurality of raised spaced apart hollow rectilinear embossments arranged in rows and 25 columns and projecting out from said front face, the edges defining the longer sides of any one such embossment being perpendicular to edges defining the longer sides of next adjacent embossments in the row and column in which said one embossment is located.

30 2. A flexible apertured panel in accordance with claim 1 in which pairs of said rectilinear raised hollow embossments intersect to form cruciforms.

35 3. A flexible apertured panel in accordance with claim 1 in which each of said embossments has a front portion spaced from said front face and an aperture extending therethrough, and an upstanding annular wall formed integrally with each said embossment extending out from the front portion thereof substantially normal to said front face to define the periphery of said aperture.

40 4. A flexible apertured panel in accordance with claim 2 including an upstanding annular wall formed integrally with each embossment and extending out from the front portion thereof substantially normal to said front face to define the periphery of said aperture, a side portion of 45 each embossment intermediate said front portion and said front face, and in which said internally formed means are integral strengthening members extending radially between said upstanding annular wall and said side portion.
